UNITED STATES PATENT OFFICE

164,620

GATE UNIT

Mary Bello, Brooklyn, N. Y.

Application April 27, 1950, Serial No. 9,519

Term of patent 3½ years

(Cl. D28—1)

To all whom it may concern:

Be it known that I, Mary Bello, a citizen of the United States, residing at 1678 83rd Street, Brooklyn, New York, have invented a new, original, and ornamental Design for a Gate Unit, of which the following is a specification, reference being had to the accompanying drawing forming a part hereof:

Fig. 2 is a sectional view taken on line 2—2 of Fig. 1.

I claim:

The ornamental design for a gate unit, substantially as shown.

MARY BELLO.
